SPARK PLUG

Ernest F. Koehler, South Berlin, and Richard Harden, Boston, Mass., assignors, by mesne assignments, to Ernest F. Koehler, South Berlin, Mass., and Gustave W. Goerner, Bourne, Mass.

Application January 6, 1937, Serial No. 119,290

2 Claims. (Cl. 123—169)

The present invention relates to spark plugs and methods of making the same.

The object of the present invention is to provide a spark plug which affords exceptionally high insulation between the electrodes, which is unbreakable, which maintains the proper sparking gap throughout its life and which is substantially free from carbonization.

With this object in view the principal feature of the invention comprises a spark plug having inner and outer electrodes which have flush or nearly flush surfaces at the sparking zone. The electrodes are separated by annular insulation which comprises wound sheet material of small thickness, this material being preferably sheet mica which is excellent for both its electrical and heat resisting characteristics.

Other features of the invention consist of certain novel features of construction and modes of operation hereinafter described and particularly defined in the claims.

In the accompanying drawing, Fig. 1 is a side elevation of one form of spark plug according to the present invention; Figs. 2 and 3 are detail views illustrating steps in the assembly; Fig. 4 is a bottom plan view of the spark plug; Fig. 5 is a detail sectional view illustrating another modified form of the invention; and Fig. 6 is a sectional elevation of a modified form of spark plug according to the present invention.

The spark plug illustrated in Figs. 1 to 4 inclusive comprises an outer electrode or shell 8 having the usual threads 10 for reception in a cylinder head, and an inner concentric electrode 12. The shell 8 has a taper bore and the inner electrode 12 is in the form of a pin having a corresponding taper. The pin is provided at its upper end with a threaded portion 14.

The inner and outer electrodes are separated by insulation designated generally at 16. This insulation comprises thin sheet material, preferably mica, wound up to produce the required insulation thickness. For example, with mica sheets two-thousandths of an inch thick, ten convolutions are required to produce a twenty-thousandths gap. Owing to the taper of the inner electrode the mica sheet from which the insulation is wound is necessarily curved as indicated at 18 in Fig. 2. The mica is wound on a mandrel to the proper size and thickness. The tightly wound mica roll is then secured by a strip of thin paper adhesive tape 20. The mica roll is inserted into the taper bore of the shell. An inner electrode 12 is then inserted into the mica roll as shown in Fig. 3 and the

inner electrode and the roll are forced into the shell by a suitable press. In this operation the mica is tightly compressed by the pressure between the tapering walls of the electrodes. When the inner electrode is forced into its proper position the parts are rigidly held against displacement. As shown by a comparison of Figs. 1 and 3, the mica roll and the taper pin are originally of somewhat greater length than in the final assembly, so that after the pressing operation they will protrude beyond the bottom end of the shell. The inner electrode and the mica are later to be machined off flush with the outer electrode as shown in Fig. 1.

After the pressing operation, the plug is provided with external body insulation, indicated in Fig. 1 as a series of mica washers 22 having an internal diameter sufficient to surround the mica roll 16. A retaining cap 24 is then threaded on the upper end of the electrode pin with sufficient force to compress the washers 22.

The insulation 22 is machined to provide a smooth exterior appearance and the protruding ends of the inner electrode 12 and the mica roll 16 are then machined off so that at the bottom face the surface of both electrodes and the mica are accurately flush. A terminal cap 26 of any suitable construction is then threaded on the upper end of the pin.

The construction described above is advantageous in that the bottom surfaces of both electrodes and the mica are substantially flush so that no indentation or protrusion of the mica with respect to the metal surfaces can be detected. In normal operation, the spark takes place between the inner or outer electrodes over the entire annulus or at more or less separated points. The flush machining of the mica with respect to the metal protects the sharp edges of the metal and assures against any change in the gap which might arise due to pitting of the metal. Furthermore, since the insulation is directly at the zone of sparking and is thereby raised to approximately the same temperature as the adjacent metal parts, carbonization of the mica is practically avoided.

The modified form of the invention shown in Fig. 5 is similar to that previously described except that the inner electrode is provided at the bottom with a protruding portion 28 of increased taper. In this construction the spark takes place between the edge of the portion 28 and the shell. This form of the invention does not provide for sparking over flush surfaces, but it has been found that carbonization and wear

are very small in comparison with spark plugs of the usual type. Furthermore, the construction has the manufacturing advantage that it permits the use of mica rolls of standard form, the gap being varied by using pins with different protruding tapers; in fact the gap may be changed even after assembly by milling off some of the protruding portion 28 either at the bottom or around the periphery.

10 The construction shown in Fig. 6 embodies a cylindrical inner electrode and hence offers the advantage of lower manufacturing cost. The shell is bored with cylindrical walls, the bore having a shoulder 32. Received in the bore is a composite mica roll comprising a roll 34 of small external diameter and protruding above the shell, and a second or bottom roll 36 of larger diameter, the upper part of which bears against the shoulder 32. Preferably the rolls are wound with an overlap, the first few convolutions of the roll 36 being wound into the last few convolutions of the roll 34. The composite roll as thus made up is inserted into the shell and the bottom surface is finished off flush with the shell. The inner electrode pin is then inserted. The pin is provided at the bottom with a conical head 46 provided with internal prongs 42 which are forced into the roll 36. The shoulder 32 positions both the mica roll and the inner electrode 20 while the prongs 42 prevent rotation under subsequent application of the retaining cap 24. The mica washers 22 and the cap 24 are applied in the manner previously described. Although this construction employs more mica, it has the manufacturing advantage over the taper construction that the mica is not required to be cut

on a curve. Furthermore, the shell and mica roll may be made in stock sizes, the gap being determined by the size of the head 46. It will be observed that the gap takes place over the surface of the mica and hence the advantages mentioned in connection with the construction of Fig. 1 are obtained, namely, freedom from carbonization and maintenance of the proper gap under all conditions.

Having thus described the invention, we claim:

1. A spark plug comprising a shell electrode having a taper bore, an inner electrode having a taper corresponding to the taper bore, the inner electrode protruding upwardly above the shell, a winding of thin sheet insulation tightly compressed annularly between the inner electrode and the shell and surrounding the inner electrode above the shell, and a body of exterior insulation above the shell and surrounding the wound insulation, the inner electrode having a portion of increased taper protruding slightly beyond and flaring outwardly under the wound insulation at the bottom.

2. A spark plug comprising a shell electrode having at the top a cylindrical bore and at the bottom a bore of larger diameter, a composite winding of thin sheet insulating material fitting closely within both bores and protruding upwardly above the top of the shell and substantially flush with the bottom of the shell, and an inner electrode fitting within the winding and having a head abutting the bottom surface thereof, the head having projections engaging with the winding.
